UNITED STATES PATENT OFFICE.

LEONARD LEROY CLOSE, OF AUBURN, INDIANA, ASSIGNOR TO AUBURN FOUNDRY CORPORATION, OF AUBURN, INDIANA, A CORPORATION OF INDIANA.

STOKER.

Application filed April 4, 1923. Serial No. 629,931.

My said invention relates to stokers for furnaces and it is an object of the invention to provide improved means for feeding the fuel off the coking grate to the main grate.

5 Another object of the invention is to provide means for admitting air to the fire above the fuel body.

Still another object of the invention is to provide means for admitting air to the mass 10 of fuel on the coking grate in a manner to cause it to pass through said mass.

Referring to the accompanying drawings which are made a part hereof and on which similar reference characters indicate similar 15 parts,

The figure is a vertical longitudinal section of a part of a furnace equipped with my fuel and air supplying means in a preferred form.

20 In the drawings reference character 10 indicates a part of the main grate of a furnace of conventional type and 11 the coking plate or grate used in connection therewith. A support 12 is provided with rollers 13 25 which form anti-friction supporting means for a ram 14 here shown as mounted to reciprocate in a horizontal plane. Upper guides for the ram are provided at 15 and a perforated plate 16 is supported by the 30 frame 12 just above the rear end of the ram, the face of the plate preferably lying in the same plane as the rear face of the ram when in its normal retracted position. The rear end of the ram is hollow and is filled 35 with any suitable refractory composition such as fire brick. The rear end is hollow and is provided with a transverse pivot 17 which carries one end of a link 18 pivoted at the other end to a bent lever 19 which is 40 mounted to rock on a pivot 20.

At the front of the plate 16 is a chamber for admission of air to the plate and adjacent the plate is a valve 21 swingably supported by a pivot 22 and having pivoted thereto at its lower end a rod 23 provided at the other end with a hand hold 24. By means of this rod the draft through the ventilating plate can be adjusted. The upper wall 25 of the chamber supports or lies 45 adjacent to bricks 26 forming a part of the lining of the furnace and sloping at the rear toward the plate 16. Above the bricks 26 is a hopper 27 open at its lower end and provided with a bottom closure 28 in the form of 50 a plate mounted for horizontal reciproca-

tion on guides located between the hopper and the bricks 26. Beneath the closure 28 is a perforated ventilating plate 29 spaced from the first named plate and held in fixed relation thereto by bolts 30. At its rear end 60 the ventilating plate is bent upwardly and thus it forms a continuation of the lining 31 of the furnace. At its front end the plate 28 is provided with a pin 32 traveling in a slot 33 of a bent lever 34 by means of which the bottom closure of the hopper may be reciprocated to admit fuel to the furnace. When so operated the fuel will run down the sloping face of the brick work to the coking 65 grate 11 or to the material resting on the 70 grate.

The lever 19 is oscillated at appropriate intervals to force the ram into the mass of fuel on the coking grate and it will be seen that when this is done the partially ignited fuel lying nearest to said grate will be moved out and fed to the main grate. This is commonly done in two steps, the ram being first forced half-way back and after a time being moved the rest of the way. When the ram is retracted the fuel which formed the upper part of the pile will fall down on the coking grate and the process will be 75 repeated.

By the use of my invention it will be seen that the preliminary ignition on the coking grate is carried out to a fuller extent than in prior constructions since all the fuel on the coking grate will be more or less ignited. The degree of the ignition at the 80 upper part of the mass can be regulated by varying the position of the valve 21.

The importance of this condition will be evident to those skilled in the art as it permits full advantage to be taken of the oily and tarry material in the fuel which is otherwise lost in the smoke.

The ventilating plate beneath the hopper also contributes to the desirable condition above explained since it has been found by experiment that where no air is admitted to the furnace above the bed of fuel a large part of the gases evolved are in the form of CO and unless air is admitted at this stage the desirable oxidation to CO₂ is not effected. 105

While I have shown my invention as embodied in a hand stoker it will be obvious to those skilled in the art that the same may be applied to a mechanically operated stoker. Numerous other modifications of the inven- 110

tion will also be obvious to those skilled in the art and therefore I do not limit myself to what is shown in the drawings and described in the specification but only as indicated in the appended claims.

Having thus fully described my said invention, what I claim as new and desire to secure by Letters Patent, is:

1. In a stoker furnace, a coking grate, a hopper arranged and constructed to feed fuel thereto said hopper having a feed opening at the bottom, a closure for said feed opening, and means for admitting air to the furnace above the fuel bed said means being movable with said closure, substantially as set forth.
2. In a stoker furnace, a coking grate, a hopper arranged and constructed to feed fuel thereto said hopper having a feed opening at the bottom, a horizontally movable closure for said feed opening, a perforated plate movable with the closure and forming part of the lining of the furnace said plate being spaced from the closure and adapted to admit air to the furnace above the fuel bed, substantially as set forth.
3. In a furnace, a front wall, a ram normally positioned with its inner face approximately in the plane of the inner face of said wall, a coking grate behind the ram, an air passage above the ram, a damper in said passage immediately above the ram, a hopper above said damper in front of the vertical inner face of the furnace wall, said wall having an inclined face below the hop-

per leading toward the coking grate, a bottom closure for the hopper, and a perforated plate spaced from the under face of said closure and movable therewith whereby a downward and inward draft of air is provided below the bottom of the hopper, substantially as set forth.

4. In a stoker furnace, a horizontal coking grate, a vertical wall at the front side of the grate, means for piling green fuel on said grate and against said wall, a main grate, a manually-operated ram to force the fuel at the bottom of the pile toward the main grate, and a perforated plate above the ram for forming a draft through the green fuel at the top of the pile toward the body of the furnace, substantially as set forth.

5. In a stoker furnace, a horizontal coking grate, a vertical wall at the front side of the grate, means for piling green fuel on said grate and against said wall, a manually-operated ram to force the fuel at the bottom of the pile toward the main grate, a perforated plate above the ram for forming a draft through the green fuel at the top of the pile toward the body of the furnace, and a damper controlling said draft, substantially as set forth.

In witness whereof, I have hereunto set my hand at Auburn, Indiana this 30th day of March, A. D. nineteen hundred and twenty-three.

LEONARD LEROY CLOSE.
